(57) **CLAIM**

We claim the ornamental design for a digital still camera, as shown and described.

DESCRIPTION

FIG. 1 is a front and right side perspective view of a digital camera of the present invention;

FIG. 2 is a rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The change in contrast represents a change in color, material or texture and does not depict any particular color, material or texture.
